UNITED STATES PATENT OFFICE.

HARVEY K. ERNSBERGER, OF NORWALK, OHIO.

GRATE FOR HEATING SYSTEMS, &c.

SPECIFICATION forming part of Letters Patent No. 625,659, dated May 23, 1899.

Application filed May 9, 1898. Serial No. 680,151. (No model.)

To all whom it may concern:

Be it known that I, HARVEY K. ERNSBERGER, a citizen of the United States, residing at Norwalk, in the county of Huron and State 5 of Ohio, have invented certain new and useful Improvements in Grates for Use in Heating Systems, &c.; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 My invention relates to an improvement in grates adapted for use in furnaces or other like heating appliances, and is particularly designed for use in combination with the heating system set forth in Letters Patent numbered 578,482 and granted to me on the 9th day of March, A. D. 1897, in the place of the grate therein described.

The object of my invention is to provide an easily-manipulated, durable, and economical 25 device of the class mentioned adapted to shake or agitate the fire-bed either wholly or in part, as desired, whereby the ashes may be made to drop into the subjacent ash-pit, while the waste of live coal is reduced to the minimum, all of which I will more fully describe 30 hereinafter.

In the accompanying drawings, Figure 1 is a general view in perspective, partly broken away, of my improved grate as it appears 35 when in position within and supported by a partially-completed brick casing. Fig. 2 is a side view of the same apart from the casing.

Similar numerals of reference when they appear indicate corresponding parts in both 40 figures of the drawings.

1 designates the partially-completed brick casing, the residue of which may be constructed in the usual manner.

2 represents a series of horizontal water-circulating pipes arranged in alignment parallel and a distance apart, one end of each of which communicates with the base portion 3 of a hollow device or manifold, the residue of which manifold may be of any suitable form, 45 but preferably of inverted-V shape, the completed whole forming a triangle. The balance of the device, or what might be termed the "grate proper," consists of a number of

grate-bars 4, which, like the pipes 2 between which they lie, are, it is plain, also arranged 55 in horizontal alignment parallel and a distance apart. The lower notched edges 5 thereof rest on and said bars are supported by cross-bars 6, the upper edges 7 of which are also notched. The notched edges 5 and 7, it is evident, are adapted to take one into the other or interlock. Parallel with said cross-bars 6 are a pair of shafts or drums 8, each being provided at or near one of its ends with a vertical lever or handle 9 and at a distance from 65 each end with a downwardly-inclined arm 10, each of which passes into and a distance through a slot 11, found in each end of the cross-bars 6 and adapted as the levers or either of them are worked to elevate one end or the 70 series of grate-bars, as the case may be, thereby agitating the fire supported thereby and by the pipes 2 to remove the ashes which drop into the subjacent ash-pit and with but little loss of live coal.

It is obvious that the pipes 2 being when in use full of water are nearly fire or heat proof and tend to preserve the adjacent grate-bars, and the heat which in other devices of this nature destroys said bars is by virtue of 80 the peculiar construction of this device beneficially utilized.

Having thus described my invention, what I claim, and desire to secure by Letters Patent, is—

In a grate, a suitable inclosing wall, a manifold arranged in the front end of said inclosing wall on a level with the grate-bars, and a series of stationary pipes which are connected to the manifold, combined with a series of 90 rocking or tilting grate-bars 4 which are placed between the pipes, a shaft extending horizontally across at each end of the grate-bars, arms 10 projecting from the shafts, and supporting the cross-pieces 6 upon which the 95 grate-bars rest; the outer ends of the shafts projecting through the inclosing wall and provided with levers or handles whereby either or both of the ends of the grate-bars may be rocked, substantially as shown and described. 100

In testimony whereof I affix my signature in presence of two witnesses.

HARVEY K. ERNSBERGER.
